CLAIM

The ornamental design for a lap desk with device slot, as shown and described.

DESCRIPTION

FIG. 1 is a left, elevated, front quartering perspective view of a new design for a lap desk with device slot;

FIG. 2 is a bottom plan view of the new design of FIG. 1; FIG. 3 is a top plan view of the new design of FIG. 1; FIG. 4 is a front elevational view of the new design of FIG. 1;

FIG. 5 is a rear elevational view of the new design of FIG. 1;

FIG. 6 is a right side elevational view of the new design of FIG. 1;

FIG. 7 is a left side elevational view of the new design of FIG. 1; and,

FIG. 8 is a front, elevational section, as indicated in FIG. 3, showing the interior shape of the device slot in the top surface of the new design of FIG. 1.
